HOSE NOZZLE

Robert E. Byars, Elmhurst, Long Island, N. Y.

Application March 7, 1938, Serial No. 194,462

2 Claims. (Cl. 299—150)

My invention relates to improvements in hose nozzles and the particular object of the invention is to equip a hose nozzle with means for closing the same when the nozzle is dropped onto the 5 ground, floor or the like.

To the accomplishment of the above, and subordinate objects presently appearing, a preferred embodiment of my invention has been illustrated in the accompanying drawings, treated in detail 10 in the succeeding description, and defined in the claims appended hereto.

In said drawings:—

Figure 1 is a view in side elevation of a hose nozzle equipped according to my invention,

15 Figure 2 is a view in longitudinal section,

Figure 3 is a view in transverse section taken on line 3—3 of Figure 2 looking in the direction indicated by the arrows and drawn to an enlarged scale,

20 Figure 4 is a similar view taken on the line 4—4 of Figure 2,

Figure 5 is a view in side elevation of the front section of the housing, and

Figure 6 is a view in perspective of the valve.

25 Referring to the drawings by numerals, the hose nozzle of my invention comprises a front section 1 and a rear section 2, the former being a tapered cylinder having a chamber 3 in the rear end thereof for a purpose presently clear and an axial bore 4 extending from said chamber to the front end of said section. The rear section 2 has the form of a cylindrical housing comprising a pair of front and rear cup-like members 5 and 6 threadedly secured together as at 7, the front member 5 30 having a front end wall 8, an axial aperture 9, and a circular series of larger apertures 10 grouped around the aperture 9. The rear member 6 has an axial nipple 11 extending therefrom exteriorly threaded, as at 12, for the attachment of the end 35 of a hose 13 thereto. The section 2 is secured to the section 1 concentrically thereof by means of screws 14 extending through the front wall of the member 5 and into the rear end of section 1.

40 Within the chamber 3 is a conical valve 15 fast 45 upon the front end of a valve stem 16 slidably mounted in the aperture 9 and having a ball 17 on the rear end thereof. The arrangement of the described valve and stem is such that upon forward movement of said stem 16 the valve 15 will 50 seat against the rear end of the bore 4 and close said bore thereby preventing the discharge of water therefrom. A tension spring 18 interposed between the wall 8 and a pin 19 on the stem 16 urges the latter rearwardly and the valve 15 into 55 opening position.

The section 2 serves as a mounting for a valve operating member adapted for functioning under impact with the ground and comprising an annulus 20 larger in diameter than the section 2 and surrounding the same, said annulus having radial 5 flat spokes 21 extending through circumferentially spaced slots 22 provided in the rear edge of member 5, said spokes extending to an annular hub 23 of smaller diameter than the inside of the section 2 and confined edgewise between the front and rear members 5 and 6 for sliding movement thereagainst into and out of axial relation to said section, it being understood that the slots 22 are properly proportioned to permit play of the spokes under such movement of said hub. Preferably 15 the hub 23 has inturned ground edges 24 engaging said members 5 and 6 to provide proper bearing surfaces on said hub. Suitably secured at its edge in the hub 23, concentrically thereof is a circular rigid diaphragm 25 disposed parallel with 20 the median plane of the hub 23. The diaphragm 25 is corrugated in concentric circles to provide a depressed axial socket 26 in its front face and a circular cam part 27 on said front face surrounding the socket 26 concentrically thereof. At suitable points said diaphragm 25 is perforated, as at 25 28, to permit the passage of water therethrough.

As will be seen from an inspection of Figure 2, if the annulus 20 and hub 23 are concentric to the section 2 the ball 17 will seat in the socket 26 and 30 permit the valve 15 to be moved to opening position by the spring 18. On the other hand if said annulus 20 and hub 23 are moved out of such concentric relation to the section 2 the ball 17 will be cammed forwardly by the cam parts 27 of diaphragm 25 and the valve 15 thereby moved into 35 closing position relative to the bore 4 of section 1.

The operation of my invention will be readily understood from the foregoing. If the nozzle is dropped to the ground the annulus 20 will engage 40 the same and under impact with the ground will be moved into eccentric relation to the member 2, in one direction or another, thereby similarly moving the hub 23 and effecting closing of the valve 15 in the manner already described. By 45 manipulation of the annulus 20 into concentric relation to the section 2 the hub 23 may be similarly moved to partition the socket 26 axially of the section 2 in which position of said socket 26, as already seen, the ball 17 will seat therein and the valve 15 be moved to opening position by the 50 spring 18. In the concentric position of the hub 23 relative to the section 2 water passes from the hose 13 through the apertures 28 in the diaphragm 25, through the hub 23 and apertures 10 into the 55

chamber 3 and from chamber 3 by way of the bore 4 outwardly of the section 1.

The foregoing will, it is believed, suffice to impart a clear understanding of my invention 5 without further explanation.

Manifestly my invention, as described, is susceptible of modification both as regards combinations of parts and features of construction and right is herein reserved to all such modifications 10 falling within the scope of the subjoined claims.

What I claim is:—

1. In a hose nozzle, a tubular discharge member having an axial bore therein, a normally open valve mounted on the rear end of said discharge member for movement axially of said bore into closing position relative thereto, and means for moving said valve into closing position comprising an annulus larger in diameter than said member and mounted on the rear end of said 20 member for movement under impacts thereagainst laterally of the axis of said member, and

operating connections between said annulus and valve.

2. In a hose nozzle, a tubular front member having a discharge bore therein, a cylindrical housing member having front and rear walls, the latter provided with an axial nipple extending therefrom for the passage of water therethrough into the housing, and the former being secured to the rear end of said front member and perforated for the passage of water from said housing member into the bore of the front member, a valve mounted in said front wall for movement axially of said bore into closing position relative thereto, said valve being normally open, means for moving the valve into closing position including an annulus surrounding said housing member and movable under impacts thereagainst laterally of the axis of the housing member, and a valve camming device in said housing member operative by such movement of said annulus. 15 20

ROBERT E. BYARS.
